UNITED STATES PATENT OFFICE.

ARTHUR W. BROWNE, OF PRINCEBAY, NEW YORK, ASSIGNOR TO THE S. S. WHITE DENTAL MANUFACTURING COMPANY, OF PHILADELPHIA, PENNSYLVANIA.

DESIGN FOR A DENTAL-ENGINE ANGLE HANDPIECE-HANDLE.

SPECIFICATION forming part of Design No. 35,182, dated October 15, 1901.

Application filed July 1, 1901. Serial No. 66,787. Term of patent 14 years.

To all whom it may concern:

Be it known that I, ARTHUR W. BROWNE, a citizen of the United States, residing at Princebay, in the county of Richmond and State of New York, have invented and produced a certain new and useful Design for a Dental-Engine Angle Handpiece-Handle; and I do hereby declare the following to be a full, clear, and exact description of the invention, such as will enable others skilled in the art to which it appertains to make and use the same.

As shown in the accompanying drawing, which is a view in side elevation, the leading or material feature of my design for a dental-engine angle handpiece-handle consists of the handle-section proper, A, the elbow-sec-

tion B, and the neck-section C. The handle is round in cross-section throughout its length, and, as shown, the handle-section proper, A, 20 is slightly swelled, the elbow-section B is angular in longitudinal section and slightly tapered toward the front of the handle, while the neck-section C is concaved longitudinally.

I claim as my invention—

The design for a dental-engine angle handpiece-handle, as herein shown and described.

In testimony whereof I affix my signature in presence of two witnesses.

ARTHUR W. BROWNE.

Witnesses:

GEO. D. HECK,
SEYMOUR CASE.
